Primary Examiner—Wallace R. Burke**Assistant Examiner—M. H. Tung****Attorney, Agent, or Firm—Steinberg & Raskin****[57]****CLAIM**

The ornamental design for a cover for a pressurized sand filter, as shown and described.

DESCRIPTION

FIG. 1 is a top perspective view of a cover for pressurized vessels showing my new designs;

FIG. 2 is a bottom perspective view thereof;

FIG. 3 is a top plan view thereof;

FIG. 4 is a top plan view thereof, on a reduced scale; and,

FIG. 5 is a side view thereof, all sides being identical, on a reduced scale.

FIG. 1

FIG. 2

*FIG. 3*FIG. 4

FIG. 5
